(57) **CLAIM**

The ornamental design for a display screen or portion thereof with graphical user interface, as shown and described.

DESCRIPTION

The sole FIGURE is a front view of a display screen or portion thereof with graphical user interface showing the new design.

The outermost evenly-dashed broken lines show an electronic device and form no part of the claimed design. The dot-dashed broken lines adjacent to the outermost evenly-dashed broken lines show a display screen or portion thereof and form no part of the claimed design. The remaining broken lines in the drawings show portions of the graphical user interface and form no part of the claimed design.
